UNITED STATES PATENT OFFICE.

WILLIAM T. LOYD, OF HIAWATHA, KANSAS, ASSIGNOR TO HIMSELF AND
HENRY P. HARRISON, OF SAME PLACE.

SHOE.

SPECIFICATION forming part of Letters Patent No. 508,328, dated November 7, 1893.

Application filed April 26, 1893. Serial No. 471,853. (No model.)

To all whom it may concern:

Be it known that I, WILLIAM T. LOYD, of Hiawatha, in the county of Brown and State of Kansas, have invented a new and Improved 5 Shoe, of which the following is a full, clear, and exact description.

My invention relates to improvements in shoes, and the object of my invention is to produce a shoe which may be made either in 10 the form of an overshoe, a sandal, or in the usual style; which may be worn over another shoe, or without any shoe, which is especially adapted for use as an ice creeper, as it prevents a person from slipping in any direction, which also is adapted for use upon rough 15 places or where it is necessary to get a good foothold, as for instance, by runners in racing, and which may be very cheaply made and easily applied to the foot.

20 To this end, my invention consists in certain features of construction and combinations of parts, which will be hereinafter described and pointed out in the claim.

Reference is to be had to the accompanying 25 drawings forming a part of this specification, in which similar figures of reference indicate corresponding parts in both views.

Figure 1 is a longitudinal section of a shoe embodying my invention, and Fig. 2 is an inverted plan of the same.

The shoe is provided with a metal sole 10, which is shaped substantially like an ordinary shoe sole, having a spring shank 11, pressed upward in the right place and having 35 at its rear end a metal counter 12, which is pressed out of the same piece as the sole, and a flange 13 around the toe and ball of the sole. At the toe of the shoe is a flexible toe-piece 14, which is fastened by any suitable 40 means to the flange 13, and which is adapted to receive the toe of the foot, while inside the counter 12 is a lining 15, also of flexible material and adapted to receive the heel, and to be easy to the same, or if the shoe is worn 45 over another shoe, to prevent injury to the inner shoe.

The shoe is provided with a strap 16, which

is adapted to extend over the instep in the same manner as a skate strap, and to buckle around the instep, and the form of shoe described is like a sandal, being a skeleton shoe.

Beneath the sole 10 and beneath the ball of the shoe, is a plate 17, which is provided with a flange 18 extending around its edge, and having serrated teeth thereon, which are 55 adapted to embed themselves in the ground or ice and prevent the shoe from slipping. The plate 17 is of the same general shape as the forward portion of the sole, and it is provided with cross bars 19, having serrated 60 flanges 20, which are of the same height as the flanges 18, and it will be observed that the arrangement of the serrated flanges 18 and 20 is such that the teeth of the flanges will press in divers directions and prevent 65 the shoe from slipping in any way. The shoe is provided with a heel-plate 21, which is substantially like the plate 17, it corresponding to the contour of the heel, and having a serrated edge flange 22, and cross flanges 23, 70 which are also serrated.

As illustrated, the plates 17 and 21 are fastened to the sole 10, but it will be understood that these plates may be formed integrally with the sole 10 if desired, without affecting 75 the principle of the invention.

Having thus described my invention, I claim as new and desire to secure by Letters Patent—

A shoe comprising a sole provided with a 80 spring shank 11 a flange 13 around the marginal edge in front of the shank, a counter forming flange in rear of the shank; the whole formed of a single sheet metal plate, the toothed metallic sole and heel plates provided with marginal and transverse serrations, the fabric toe piece 14 secured to flange 15, the counter lining 15 and the strap 16, substantially as set forth.

WILLIAM T. LOYD.
